KEYLESS LOCK

William W. Hurtel, Los Angeles, Calif.

Application April 25, 1944, Serial No. 532,641

5 Claims. (Cl. 70—298)

1

This invention relates to a keyless lock. Speaking more specifically the invention pertains to a lock furnished with a series of tumblers, a predetermined group of which must be moved from their normal position until arrested by stops while all the remaining tumblers remain undisturbed, before the bolt of the lock can be released, all the tumblers of the lock being manually operable so that the initiated person, who knows what combination of tumblers must be adjusted to release the bolt, can operate the lock without using a key.

Among a great number of situations wherein the invention may be used to advantage, may be mentioned for locking garages, gates, all types of out buildings, farm buildings, and for locking office doors and entrances through railing and other office partitions, and for locking various types of drawers, cabinets, cupboards, and the like.

Among the objects of the invention are to provide, for interchangeable use in the lock, a set of improved tumbler stop members for each lock, said members desirably consisting of strips of rigid sheet material capable of being stamped out at low cost by dies, or of being made from plastic material; to provide tumblers which are particularly well adapted for being moved from their normal to their adjusted position by being directly engaged by the fingers of the operator; and to provide a set of manually liftable tumblers which can be more safely depended on to gravitate from their lifted, stop-releasing position to their normal locking position.

Other objects, advantages and features of invention will hereinafter appear.

Referring to the accompanying drawing, which illustrates what are at present deemed to be preferred embodiments of the invention,

Fig. 1 is a front elevation of the device with the face plate and operating handles removed, the tumblers being in bolt releasing position. A few parts are sectioned on line 1—1 of Figs. 2 and 4, and some other parts are broken away in order to disclose underlying structures.

Fig. 2 is in general a longitudinal section of the device, including the face plate and handle means, the plane of section being indicated by the line 2—2 on Fig. 1. In this view the spring, the locking bolt and a portion of the operating knob and of certain tumblers are shown in side elevation.

Fig. 3 is another longitudinal section of the device, the plane of section being indicated by angular line 3—3 on Fig. 5.

2

Figs. 4 and 5 are cross sections of the device taken respectively on the planes indicated by lines 4—4 and 5—5 on Fig. 1.

Fig. 6 is a perspective view showing an example of a combined bolt carrier and tumbler stop plate which may be substituted for the corresponding plate of Fig. 1 to vary the combination of tumbler elements which it is necessary to adjust before the locking bolt can be released.

Fig. 7 is a detailed perspective view of a single special tumbler which is one of a pair of tumblers which cooperate with the same stop means on the bolts or bolt carriers.

Fig. 8 is a detailed perspective view of the other tumbler of the above mentioned pair.

Fig. 9 is a cross section on line 9—9 of Fig. 1, illustrating stop means which cooperate with a specific group of tumblers, the midwidth part of the device being broken out to contract the view.

Fig. 10 is a perspective view of an alternative construction, showing a locking bolt which does not require a carrier and embodies in itself the stop means with which the tumblers cooperate.

Fig. 11 is a perspective view of the device modified for use principally to lock liftable doors, the enclosed portion of the locking bolt of Fig. 10 being usable in this and similar situations or wherever locking bolts of this modified design are required.

Referring in detail to the drawing, the elongated casing shown comprises a generally rectangular face plate 12, back plate 13 and fastening means shown as bolts 14 passing through corner portions of the casing to hold said two plates together. Suitable flanges are shown on said plates to close in the sides and ends of the casing, said face plate having along its upper edge a backwardly directed flange 15 which engages the outer face of a like flange 16 of the back plate. Corresponding to said flanges 15 and 16, the casing plates have bottom flanges 17 and 18, but these are cut away at 19 as shown in Figs. 4, 5 and 11 (the latter being a modification in regard to the locking bolt only), to provide manual access to the liftable tumblers of the lock.

The elongated locking member of Figs. 1 to 5 consists of two principal parts, a locking bolt 21 and a locking bolt carrier 22. Said bolt has a beveled locking head 23 and the carrier is provided at its back side with a projection 24 affording a shoulder 24a which may be used to limit the retractive movement of the bolt. Adjacent to its opposite or inner end said bolt car-

rier has another projection 24b, said two projections spacing the intervening portion of the bolt away from the back plate 13, thereby providing a working clearance for the tumblers hereinafter described. Also the bolt has at its inner end a preferably integral stem 25, the end of which carries a head 26 which alines with the body portion of the bolt.

Returning to the bolt carrier 22, this member is shown formed of a single piece of rigid metal or plastic sheet material which is shaped to form a channel having interrupted side walls within which the bolt 21 is fitted to move longitudinally in relation to the carrier from an extended to a retracted position, this movement automatically taking place when a door carrying the lock is moved to a closed position causing the beveled head of the bolt to be retracted by engaging a striking plate mounted at one side of the door opening.

In order to utilize the bolt carrier as a tumbler controlled means for manually retracting the bolt said carrier has a bolt operating end edge portion or flange portion 27 which has its back edge deeply notched at 27a to provide a working clearance for the aforesaid bolt stem 25. At times said flange 27 is moved against the head 26 of the stem 25 to retract the bolt 21, both retractive movements of the bolt being opposed by a coil spring 28 one end of which engages the head 26 and the opposite end of which abuts against a casing end wall formed by a flange 29 carried by the back plate of the casing. Sheet metal, or plastic, spacing boxes 30 and 31 are shown to fill in properly the spaces at each side of said spring and also to assist in guiding the movement of the locking bolt 21 and carrier 22.

In order to secure the desired cooperation between the bolt carrier 22 and the adjustable tumblers presently to be described, said carrier is furnished along each of its sides with a series of stops, these stops being formed by angular flanges with which said carrier is provided when it is stamped out of sheet metal, or otherwise manufactured. The character of these stop flanges is most clearly shown in Fig. 6, which view, however, shows a carrier 22x having a different arrangement of said stop flanges, for it is designed with a view to being substituted for said carrier 22 or for any other pattern of carrier belonging to a set of combination-changing carriers to be used when it is desired to change the combination of tumblers which must be operated in order to release the locking bolt.

Describing from left to right (Figs. 1, 2 and 3), the stop flanges of the carrier 22, and the tumblers which cooperate with them, the stop flange 35 extends from the upper side of the carrier near its left end and is of the same rightangular shape as the flange 36 which extends from the opposite side of the bolt carrier a little farther to the right (see Fig. 6 also), but said flange 35 is much narrower than said flange 36. With the stop shoulder afforded by the right hand edge of the flange 35 cooperate the tumblers 37 and 38, which are respectively separately shown in Figs. 8 and 7, the locking bolt being retractable only when both of these adjacent tumblers, along with certain others, are lifted from their locking position to the position shown in Fig. 1. Said tumbler 37 is shown having at one end a right angular deflected and then rebent upper end portion 37a the terminal part of which parallels the body portion of the tumbler in a considerably spaced relation thereto, and at its opposite end this

tumbler has an arcuately rebent end portion 37b the terminal part of which also parallels and is spaced away from the body portion of the tumbler. The offset parts 37a and 37b are both directed toward the front side of the casing. The tumbler 37 also has a notch 37c cut centrally in its left edge as a space economizing feature, said notch providing additional space for the travel of the projection 24 of the shoulder 24a of the locking bolt carrier or shoulder 24a of the substitute locking member 70 of Fig. 10, when the latter is used.

The tumbler 38 has a forwardly deflected upper end portion 38a which carries, preferably integral therewith, a rectangular plate 38c which corresponds in position and function to the terminal rebent part of 37a of the tumbler 37, for both part 37a and 38c engage the flange 35 of the bolt carrier to obstruct retraction of the locking bolt whenever the tumblers 37 and 38 are allowed to gravitate to their lower position. From Fig. 7 it is seen that said plate 38c is about twice as long as wide and has one of its corner portions secured to the part 38a, and the leftward extent of the plate being sufficient to span the space occupied by the tumbler 37, so that the tumbler 38, as well as 37 may engage the bolt carrier flange 35 to obstruct retraction of the bolt 21, hence either one or both of these tumblers can make this obstruction. The lower end portion of the tumbler 38 (from the viewpoint of its mounted position) has a rebent part 38b corresponding in size, shape and position to the already described part 37b of tumbler 37.

In Fig. 9 is shown a tumbler 40 which is typical of the three tumblers designated by same numerals in Fig. 1. Each of these tumblers 40 terminates at its upper end in a flange 40a which is forwardly directed at a right angle to the body of the tumbler.

The already mentioned casing flange 16 has a downwardly directed lip 16y. Said lip extends along the entire space occupied by all the tumblers shown and serves as a stop means to limit the downward gravitation of each of the three tumblers 40, and it also supports them in a bolt releasing position. If a person who does not know the combination raises one or more of these tumblers 40, he will be as positively locked out as he would be if he failed to raise any one or more of the other four tumblers. It is necessary that said lip 16y extend along the entire space occupied by the tumblers, as above stated, in order to make the tumblers and the two carriers 22 and 22x (or additional ones) interchangeable in making changes in the combinations.

Each tumbler 40 is shown furnished with a rebent lower end portion 40b, which feature is found in all the tumblers 40. Also all of said three tumblers, as indicated at 2 in various places in the drawing, are shown having a finger depression which makes it easier, particularly when operating the lock in the darkness, to locate the fingers on only the proper tumblers to be operated.

Referring to additional stop shoulders of the bolt carrier 22, besides those already mentioned in connection with its flanges 35 and 36, these additional flanges will be more readily understood by noting first the similar stop flanges of the substitute bolt carrier 22x of Fig. 6, which is furnished from left to right with angular stop flanges a, b, c, d, e and f. From the upper side of the bolt carrier 22 project (naming them from left to right), angular stop flanges 41, 42 and 43, each

of which are shaped like the flanges *c* and *e* of Fig. 6. The same side of the bolt carrier 22 also has two intervening bolt channel forming flanges 44, one of which appears in section in Fig. 5, besides the channel forming flanges 46, 47 and 48 dottedly indicated in Fig. 1. Along the lower side of the carrier, from left to right are the channel forming flanges 49, 50, 51 and 52 (the latter a long flange), dottedly indicated in Fig. 1; and, in addition to the broad stop forming flange 36 already mentioned, the angular stop forming flanges 53 and 54.

Tumblers 56 and 57 alternate with the aforesaid tumblers 40. These intervening tumblers will be readily understood from the sectional showing of tumbler 57 in Fig. 5, it being understood that these two tumblers are alike except that 57 has a slot 57s cut into its lower end to allow a turnable headed pin 59 to pass through the casing, said pin having tightly secured to it within the casing a forked arm 60 which straddles an apertured edge portion of the flange 54 of the locking bolt carrier. Arm 60 may be suitably modified for connection with the locking bolt itself if no locking bolt carrier is used. A thumb piece 61 is secured to the projecting front end of said pin 59 to afford a means for retracting the locking bolt carrier, or the locking bolt when no carrier is used. A screw 62 is shown screwed into a socket provided for it in the pin 59 to attach the thumb piece to the pin. This thumb piece, however, is only an auxiliary means for retracting the bolt carrier 22, or the bolt only.

There is also shown a retracting knob 63 which is fastened onto a threaded stud 64, the inner end of which is welded or otherwise secured to the locking bolt carrier, or to the locking bolt itself when no carrier is used. The face plate 12 of the casing has through it a longitudinal slot 65 to unobstruct the movement of said stud 64.

When thin sheet material is used to construct the bolt carrier, a reinforcing head 66 (Fig. 2), may be welded to the screw and to the sheet metal of the carrier, the locking bolt being provided with an elongated recess 67 extending longitudinally thereof to provide a working clearance for said welded-on head.

It will be observed that the various tumblers shown consist of straps of rigid sheet material which have their end portions bent toward the same side to provide them with sturdy, easily manufactured stop-engaging flanges.

In Fig. 10 is shown a modified locking bolt 70 the body portion of which has, naming them from left to right, a series of stop projections 70a, 70b, 70c, 70d, 70e and 70f, these stop projections respectively corresponding in size and position to the stop means afforded by the flanges *a* to *f* of the substitute bolt carrier 22x. The end portions of the modified locking bolt 70 are of the same shape and size as those of the locking bolt 21 except that the latter bolt has a beveled head 23, whereas the modified bolt has a square head 23x. A notch 70n is provided in projection 70f of the bolt 70 to provide an operating space for the retracting arm 60 carried by the manually turnable pin 59, it being unnecessary to slot said arm in this situation.

In Fig. 11 the lock is shown on a reduced scale constructed the same as in Figs. 1, 2 and 3 except that the locking bolt is provided with an extension 72, shown directed downwardly, carrying at its lower end a beveled latching head 73. Among other uses to which the lock of Fig. 11 is adapted to be put is to lock an upwardly and downwardly

movable garage door to the floor or door sill of the garage. It is to be understood that this modified lock will be attached to the lower edge portions of such garage doors, so that the user, after lifting the lock-releasing tumblers, will continue the upward pressure of his fingers to open the door, the lock constituting a handle means for lifting the door to its open position.

I claim:

1. In a lock of the kind described, a casing, an elongated at times longitudinally movable locking bolt carrier mounted in said casing, a locking bolt carried by said carrier and independently movable in a lengthwise relation thereto, said locking bolt being given its independent movement by closing the door, said carrier consisting of rigid sheet material having oppositely projecting side flanges to form tumbler engaging stops, and a series of elongated tumblers the individuals of which extend in a crosswise adjacent relation to said carrier to cooperate with its stops and are supported by said casing for selective manual longitudinal movement to adjust them to release said carrier to permit of its retraction together with the locking bolt which it carries.

2. In a lock of the kind described, a casing, an elongated at times longitudinally movable locking bolt carrier mounted in said casing, a locking bolt carried by said carrier and independently movable in a lengthwise relation thereto, said carrier consisting of rigid sheet material and having an elongated back plate portion furnished along each of its side edges with an inner row of angularly directed flanges, said flanges and plate portion cooperating to form a channel within which the locking bolt has a working fit, and other flanges projecting from said back plate portion which alternate with the first recited flanges along each side of said carrier to form stops, and adjustable tumblers carried by the casing to cooperate with said stops.

3. The subject matter of claim 2, and the last recited flanges having their inner portions in the same plane as said plate portion and their terminal portions projecting toward the channeled side of said carrier.

4. In a lock of the kind described, a casing, an elongated locking member mounted therein to be longitudinally moved at times, said member carrying a longitudinally extending series of laterally projecting stops, and a series of manually adjustable tumblers carried by said casing to cooperate with said stops, said series of tumblers comprising a pair of adjacent tumbler strips of rigid material which are slideable transversely in relation to said locking member, and both of which cooperate with the same stop of said locking member, the members of said pair of tumbler strips occupying different adjacent positions in relation to the length of said locking member, and one of them having an extension which reaches across the other and is engageable with the same stop on said locking member as that with which its mate cooperates, thereby causing said paired tumbler members to perform the same function in the same manner, and making it necessary to operate the two of them as a unit in releasing the locking member for retraction.

5. In a lock of the kind described, a casing, an elongated locking member mounted therein to be longitudinally moved at times, said member carrying a longitudinally extending series of laterally projecting stops, and a series of manually adjustable tumblers carried by said casing to co-

operate with said stops, said series of tumblers comprising a pair of adjacent tumblers which are slideable transversely in relation to said locking member, and both of which cooperate with the same stop of said locking member, the tumblers of said pair occupying different adjacent positions in relation to the length of said locking

member and one of them having an extension which is engageable with the same stop on said locking member as that with which its mate cooperates, thereby making it necessary to operate both of the tumblers of said pair before the locking member can be released.

WILLIAM W. HURTEL.
